UNITED STATES PATENT OFFICE.

AXEL LEVEDAHL, OF AURORA, ILLINOIS, ASSIGNOR TO INDEPENDENT PNEUMATIC TOOL COMPANY, OF CHICAGO, ILLINOIS, A CORPORATION OF DELAWARE.

STUFFING BOX.

Original application filed July 30, 1919, Serial No. 314,374. Divided and this application filed May 27, 1920. Serial No. 384,515.

To all whom it may concern:

Be it known that I, AXEL LEVEDAHL, a citizen of the United States, residing at Aurora, in the county of Kane and State of Illinois, have invented new and useful Improvements in Stuffing Boxes, of which the following is a specification.

This invention relates to stuffing boxes particularly adapted for pneumatic tools of that type wherein the piston in the barrel has a rod extending through an end of the barrel and there carries the part which operates against the work upon the reciprocation of the piston in the barrel.

The invention consists in the matters hereinafter described and more particularly set forth in the appended claims.

In the accompanying drawings—

Fig. 1 is a side elevational view of a pneumatic sand rammer embodying a stuffing box of my invention;

Fig. 2 is a longitudinal sectional view through the forward end of the barrel of said tool and showing the stuffing box in section;

Figs. 3 and 4 are transverse sectional views taken on lines 3—3 and 4—4, respectively, of Fig. 2; and

Fig. 5 is a side elevational view of the locking pin and its spring, removed from the tool.

In the drawings, I have shown the stuffing box of my invention embodied in a pneumatic sand rammer of the floor type, such as is described and claimed in my co-pending application Serial No. 314,374, filed July 30, 1919, and of which the present application is a division.

As shown herein, said sand rammer has a barrel 1, to the inner end of which is secured a valve housing or head 2 containing a distributing valve of the differential pressure area type, as well known in this art. To the head 2 is secured a throttle valve stem 3, through which live air is supplied to the tool. For controlling the air supply, a throttle valve is mounted in the stem, and the valve is held normally closed by a spring and moved into open position by the operator grasping a lever 4 pivoted on the outside of the stem and moving it toward and against the stem. The barrel 1 has the usual bore 5 for a reciprocating piston 6 provided with a rod 7 extending through and beyond

the outer end of the barrel. To the outer end of the rod is removably secured a stamper or peen 8, the latter, as shown in the drawings, having a circular stamping face, but one having a rectangular or other shaped stamping face could be used. The barrel is provided with the usual passages 9 for the operating fluid, the admission and exhaust of which to and from the barrel for reciprocating the piston being controlled by the distributing valve in the housing or head 2. As set forth in my said copending application, the overall length of the tool is such that it permits the operator to handle and operate the tool while standing in an erect position, with the stamper or peen 8 reaching a molder's flask on the floor.

The piston rod 7 extends through the stuffing box 10 of my invention, and to hold the piston and its connected-rod 7 against rotation, the stuffing box is constructed to have parts to interlock with the barrel 1 and fit in a plurality of longitudinally extending flutes or grooves 11, 11 in said rod. Said box comprises a metallic inner ring 12 bearing flatwise against an annular shoulder 13 at that end of the barrel. This ring may or may not be provided with inwardly projecting pistons to fit in the flutes 11. There is a second ring 14 in the barrel, and this ring has an outwardly projecting radial lug 15 (Fig. 4) extending into a longitudinal groove 16 in the barrel. This groove 16 opens through the outer end of the barrel to permit the ring 14 to be inserted into and removed therefrom. Between said rings 12 and 14 are interposed compressible gaskets 17 preferably of chrome friction leather. The outer ring 14 and gaskets may also be provided with parts fitting in the flutes 11.

To hold the gaskets compressed, I provide a nut having a body 18 screwed into the open end of the barrel about the piston rod. The nut acts on the outer ring 14 to force it toward the inner ring 12 and compress the gaskets 17 between them. The engagement of the lug 15 on the ring 14 with the groove 16 holds the ring from turning when loosening or tightening the nut, and further serves to hold the packing 17 from turning when compressed and thus prevents the piston and connected rod from turning during their reciprocation or at other times. The head 19 of the nut is beyond the end of the barrel

and is larger in diameter than the body portion 18, as shown. The head has one or more peripheral holes 20 to receive a spanner wrench or other device to tighten or loosen 5 the nut or to remove it entirely. To lock the nut against accidental turning and thus prevent relieving the compression on the gaskets, I provide in the face of the head 19 toward the barrel, a plurality of circumferentially spaced, countersunk depressions or recesses 21, 21, and with which cooperates a locking pin 22 projecting beyond the end of the barrel and having a conical shaped outer end to enter said depressions and to ratchet 10 therewith in the turning of the nut. The depressions have a complementary shape for this purpose. By this feature, the pin will slip from one depression to another as the nut is turned, thus avoiding the necessity of 15 being required to manually withdraw the pin from each depression before the nut may be turned. Said pin 22 is slidably mounted in a recess 23 formed in the end of the barrel and which recess is longer than the 20 pin. The inner end of the pin is reduced as at 24 to receive the adjacent end of a coiled expansion spring 25, which forces the pin forwardly toward and holds it yieldably in engagement with the head 19. The last several loops 26 at the opposite end of the 25 spring are of a diameter slightly in excess of that of the recess 23 to frictionally hold the spring therein, and as the loops at the opposite end of the spring tightly engage the reduced end 24 of the pin, the latter and the spring are prevented from dropping or being projected out of the recess 23 when the nut is removed. Thus, the pin is carried by the barrel and will not be lost or misplaced 30 when the nut is removed. The nut may be readily turned to increase or decrease the amount of compression on the gaskets, and the pin 22 will hold the nut from accidental turning and thus hold the compression on 35 the gaskets.

The pin 22 is provided adjacent its outer end with a groove 27 to permit a screwdriver or other implement to be engaged with the pin to loosen the same should it bind or stick in its recess 23, and also to enable the pin to be completely removed from 40 said recess whenever the occasion demands.

While I have shown and described herein in detail my improved stuffing box as embodied in a sand rammer of the kind shown,

it is to be of course understood that the box could be equally as well embodied in other types of tools where stuffing boxes are needed. Furthermore, it is to be understood that the details of construction and arrangement 65 of parts shown and described may be variously modified and changed without departing from the spirit and scope of my invention.

I claim as my invention:

1. In a locking device, the combination with a body member, of a nut screwed thereon and having a flanged head with a plurality of conical recesses facing said body member, a locking pin slidably mounted in 70 said body member and having a conical outer end to engage said recesses for holding the nut against accidental rotation, and a spring in said body member pressing outward against said pin for yieldably holding 75 the same against said head, said spring tightly engaging the body member and pin, respectively, for holding the pin from dropping from the body member when the nut is removed.

2. In a locking device, the combination with a body member, of a nut screwed thereon and having a flanged head with a plurality of conical recesses, a locking pin slidably mounted in a bore in said body member and having a conical outer end to engage said recesses, said pin having a reduced inner end, and a spring in said bore behind said pin for pressing the same outward against said head, said spring having the loops at 80 one end tightly engaging about the reduced end of said pin and having the loops at its opposite end slightly greater in diameter than said bore for holding the spring and pin therein when the nut is removed.

3. In a locking device, the combination with a body member, of a nut screwed thereon and having a flanged head with a plurality of conical recesses facing the body member, and a spring pressed locking pin slidably mounted in the body member and having a conical outer end to engage said recesses, said pin having an annular groove adjacent its conical end and accessible between the nut and body member.

In testimony that I claim the foregoing as my invention, I affix my signature this 24 day of May, A. D. 1920.

AXEL LEVEDAHL.
